United States Patent Office

Des. 221,416
Patented Aug. 17, 1971

221,416

CHAIN SAW WARNING DEVICE OR SIMILAR ARTICLE

Donald Jennings, P.O. Box 237, Cascade, Idaho 83611

Filed Dec. 11, 1969, Ser. No. 20,458

Term of patent 14 years

Int. Cl. D8—02

U.S. Cl. D8—70

FIG. 1

FIG. 2

FIG. 3

FIG. 1 is a front perspective view of a chain saw warning device or similar article showing my new design, associated with a chain saw shown in broken lines for illustrative purposes only.

FIG. 2 is a front perspective view of a chain saw warning device of this invention drawn to a larger scale.

FIG. 3 is a rear perspective view of the device of the present invention as viewed from the bottom.

I claim:

The ornamental design for a chain saw warning device or similar article, substantially as shown and described.
